(57) CLAIM

I claim the ornamental design for a candelabrum, as shown and described.

DESCRIPTION

FIG. 1 is a front view of a candelabrum showing my new design, the rear view being a mirror image thereof;

FIG. 2 is a left side view thereof;

FIG. 3 is a right side view thereof;

FIG. 4 is a top plan view thereof; and,

FIG. 5 is a bottom plan view thereof.

1 Claim, 2 Drawing Sheets

FIG. 1.

FIG. 2.

FIG. 3.

FIG. 4.

FIG. 5.
